US0D1038976S

(12) **United States Design Patent** (10) Patent No.: **US D1,038,976 S**
(45) Date of Patent: ** Aug. 13, 2024

(54) **DISPLAY SCREEN OR PORTION THEREOF
WITH GRAPHICAL USER INTERFACE**

(71) Applicant: **Lutron Technology Company LLC**,
Coopersburg, PA (US)

(72) Inventors: **Rhythm Agarwal**, Bethlehem, PA (US);
Benjamin F. Bard, Zionsville, PA (US); **Erica L. Clymer**, Northampton, PA (US); **Shenchi Tian**, Easton, PA (US)

(73) Assignee: **Lutron Technology Company LLC**,
Coopersburg, PA (US)

(**) Term: **15 Years**

(21) Appl. No.: **29/801,031**

(22) Filed: **Jul. 26, 2021**

Related U.S. Application Data

(63) Continuation of application No. 29/697,909, filed on Jul. 12, 2019, now Pat. No. Des. 928,816, which is a continuation of application No. 29/612,918, filed on Aug. 4, 2017, now Pat. No. Des. 854,036.

(57) **CLAIM**

The ornamental design for a display screen or portion thereof with graphical user interface, as shown and described.

DESCRIPTION

The sole FIGURE shows a display screen or portion thereof with graphical user interface showing our new design. The peripheral dashed broken lines illustrate a display screen or portion thereof, and form no part of the claimed design.

The interior dashed broken lines and the faded portion between the peripheral dashed broken lines and the interior dashed broken lines forms no part of the claimed design. Shading represents tonal contrast.

1 Claim, 1 Drawing Sheet
